UNITED STATES PATENT OFFICE.

G. B. BAILEY, OF GREENFIELD, INDIANA.

GRAIN-SCREEN.

Specification forming part of Letters Patent No. 42,635, dated May 10, 1864.

To all whom it may concern:

Be it known that I, G. B. BAILEY, of Greenfield, in the county of Hancock and State of Indiana, have invented a new and Improved Grain-Screen; and I do hereby declare that the following is a full, clear, and exact description of the same, reference being had to the accompanying drawings, making a part of this specification, in which—

Figure 1 is a vertical longitudinal section of my invention, taken in the line xx , Fig. 2; Fig. 2, a transverse vertical section of the same, taken in the line yy , Fig. 1.

Similar letters of reference indicate corresponding parts in the two figures.

This invention consists in the employment or use of a rotating screen in connection with a suction-fan and a valve, all constructed and arranged in such a manner that the grain will be deprived of all impurities, and the screen rendered capable of being supplied with grain with the greatest facility, and the latter, when properly screened and cleansed, allowed to be very readily discharged from the screen.

To enable those skilled in the art to fully understand and construct my invention, I will proceed to describe it.

A represents a framing of rectangular form, and constructed in any proper manner to support the rotary screen B, which is composed of a polygonal frame having wire or other screens b inserted in every alternate side, or in more of the sides, if desired. Within this rotary screen there are attached longitudinally a series of strips, c, to catch the grain and carry it up as the screen rotates, so as to insure a proper agitation of the grain. (See Fig. 2.)

In one end of the frame of the screen there is inserted at right angles with its shaft C a disk, D, provided with one or more openings, d, (four are shown in Fig. 2,) said openings being of conical form, larger in diameter at their inner than at their outer orifices, as shown clearly in Fig. 1.

E is a fan-case, which is secured to the end of the screen where the disk D is placed, and F is a fan, the blades e of which are bent or curved in spiral form, and are attached to a collar, f, placed loosely on the screen-shaft C.

The collar f has a pulley, G, upon it, around which and a pulley, H, on a shaft, I, a cross belt or cord, g, passes. The shaft I is in the lower part of the framing A, and receives its

motion by means of a belt or cord, h, which passes around a pulley, J, at the closed end of the screen, which is opposite to that where the fan F is placed, and around a pulley, i, on the shaft I. The fan F, in consequence of the belt or cord g being crossed, rotates in a reverse direction to the screen B, as indicated by the arrows in Fig. 2.

In one side of the screen B there is placed a valve, K, which extends nearly the whole length of the screen, and is secured to the screen-frame by hinges a* and opens inward. This valve has a metal plate, j, attached to its inner end and curved inward, as shown in Fig. 2.

L represents a case of polygonal form, which encompasses the screen B and has an opening or space, k, at its lower end. One side, l, of the case L, adjoining the space k, is hung on pivots m, and this side l is rather wider than any of the others, so that its lower part may form a chute for the escape of the screenings, when said side l has its upper end secured in contact with the side l' immediately above it, as shown in tint in Fig. 2.

The side m of the case L, above the side l', is movable in consequence of being fitted in grooves n in the sides of the framing A. This side m is formed of two parts connected by hinges o, and when the screen B is to be filled with grain the side m is drawn out from the grooves n and inserted in grooves p, and said side is then converted into a chute or feed-board to feed the grain into the screen through the valve K, the latter, when at the upper part of the screen, opening by virtue of its own gravity. When the screen is supplied with a requisite quantity of grain, the side m is placed in its proper position to form a part of the case L, and the side l is also placed as shown in tint in Fig. 2, and a rotary motion imparted to the screen B by any convenient power. The fan F draws out from the grain in the screen smut, chaff, dirt, and all light impurities. The screenings pass off from the lower end of the side l. The valve K, when passing below the shaft of the screen, remains closed by its own gravity, so that the grain cannot escape through it, and when the grain is perfectly cleansed the screen is turned backward, so as to bring the valve K at the bottom, and said valve will be open in consequence of the action of the grain against the curved plate j,

and the side *l* being previously turned down, as shown in red outline in Fig. 2, the cleansed grain is conducted thereby into any proper receptacle.

Having thus described my invention, what I claim as new, and desire to secure by Letters Patent, is—

1. The rotary screen *B*, in combination with the fan *F* and disk *B*, provided with one or more openings, all arranged to operate sub-

stantially as and for the purpose herein set forth.

2. The valve *K*, fitted in one of the sides of the screen *B*, provided with a curved plate, *j*, substantially as and for the purpose specified.

G. B. BAILEY.
